UNITED STATES PATENT OFFICE.

ABNER L. SMITH, OF GOOSE CREEK, TEXAS.

BACK-PRESSURE VALVE FOR OIL AND ARTESIAN WELLS.

Application filed October 14, 1922. Serial No. 594,480.

To all whom it may concern:

Be it known that I, ABNER L. SMITH, a citizen of the United States, residing at Goose Creek, in the county of Harris and State of Texas, have invented certain new and useful Improvements in Back-Pressure Valves for Oil and Artesian Wells, of which the following is a specification, reference being had to the accompanying drawings.

10 This invention relates to improvements in back pressure valves for oil and artesian wells.

An important object of the invention is to provide a device for sealing the lower end of the well screen to prevent the entrance of mud, water, sand and the like thereto which would tend to clog the screen.

A further object of the invention is to provide means of this character having a valve yielding under internal pressure of the pipe to permit washing of the screen in seating the same and having means whereby the valve may be positively seated to prevent flow when the same is not desired.

25 A still further object of the invention is to provide a device of this character which is simple in its construction and arrangement, durable in service, readily applied, and a general improvement in the art.

30 These and other objects I attain by the construction and arrangement shown in the accompanying drawings wherein for the purpose of illustration is shown a preferred embodiment of my invention and wherein like reference characters designate like parts throughout.

In the drawings:—

Figure 1 is a side elevation partially in section showing a back pressure valve constructed in accordance with my invention applied to an oil well;

Figure 2 is a vertical sectional view through the back pressure valve;

Figure 3 is a bottom plan view of the packing gland employed at the upper end of the wash pipe receiver;

Figure 4 is a plan view of the lower check valve;

Figure 5 is a side elevation thereof;

50 Figure 6 is a section through the main valve; and

Figure 7 is a plan view thereof.

Referring now more particularly to the drawings, the numeral 10 indicates a well casing, 11 a packer carried by the lower end of the well casing and 12 a screen se-

cured to the lower end of the well casing and adapted to screen from oil or water entering the casing all fine particles which might be contained therein. As is well known to those familiar with the art, the lower ends of these screens are usually provided with threads, as indicated at 12^a, and to these threads by means of the usual collar 13 applied thereto I attach my back pressure valve which is generally indicated at 14. This back pressure valve comprises a casing 15 threaded interiorly at its upper end, as at 16, and exteriorly at the same end, as indicated at 17, for coaction with the collar 13. The lower end of the valve casing is likewise threaded interiorly, as at 18, and exteriorly, as at 19, for the purpose presently to appear.

Into the upper end of the casing 15 I 75 secure a valve cage 20 embodying a body portion 21 which is exteriorly screw-threaded for engagement with the threads 16 and which has a bore 22. The lower end of the body portion has a depending tube like 80 extension 23 the bore of which is the same diameter as the bore 22 of the body portion. The walls of this tube like extension have formed therethrough, adjacent the upper end thereof, openings 24 and adjacent the 85 lower ends thereof other openings 25, the purpose of which will presently appear. Screw-threaded in the enlargement at the upper end of the bore 22 is a valve seat holder 26 having at its lower interior edge 90 a seat of soft metal such as lead, indicated at 27. Slidably mounted within the bore 22 of the body portion and tubular extension 23 is a piston valve 28. This piston valve has formed upon the upper end thereof sharp edges, indicated at 29, adapted to engage against and seat in the annular soft metal seat 27 hereinbefore described. The lower end of the tube like extension 23 has secured thereto a valve spring seat 30 100 against which seats one end of a spring 31, the opposite end of which engages against the lower end of the valve to force the same upwardly into engagement with the seat 27. The piston valve 28 comprises a body portion 32, upon the upper face of which is formed the sharp edge 29 for engaging the seat 27. This end has formed centrally thereof a slight extension, indicated at 33, and to which is secured a swivel eye 34 105 with which a wire 35 is engaged for a purpose presently to appear. The lower end

of the body portion 32 is provided with a reduced extension 36 and the body portion upon its outer surface has a step reduction 37. The reduced extension 36 has seated thereon against the body portion 32 a collar 38 which has formed in the lower portion of the periphery a step reduction 39. That portion of the extension 36 of the body portion projecting below the collar 38 is externally screw-threaded for engagement with a retaining member 40 having at its lower end a reduced flange 41 and having extending downwardly therefrom guide fins 42, the exterior surfaces of which are curved for slidable engagement with the walls of the bore 22 and the interior of the tube like extension 23. In assembling the piston valve prior to placing the collar 38 in position, a packing ring 43 is placed about the step reduction 37 and the collar when placed in position, retains this ring in position. Similarly upon the step reduction 39 a ring 44 is placed, and this ring is in turn held in position by the retaining member 40. Through the retaining member and the extension 36 a cotter pin 45 is placed, the reduction of the retaining member at 41 permitting placement of this pin without danger of its coming into contact with the walls of the bore of the tube like extension.

Threaded within the lower end of the valve casing 15 is a check valve seat 46 having a central aperture in which is seated a check valve 47, being provided about this aperture with a raised ridge or shoulder 48. The check valve seat 46 is of considerable thickness and the central opening thereof affords a guide for the check valve which is provided with relatively long guide vanes 49. Upon its lower face the check valve has a downwardly extending portion 50, the lower end of which comes in contact with a central abutment 51 formed upon a spider 52 having threaded engagement in the lower end of the valve casing beneath the seat 46, prior to the disengagement of the guide vanes 49 from the seat 46 so that there is no danger of this valve being lost from its seat. Between the spider and the valve a spring 53 extends which surrounds the extension 50 of the valve and the abutment 51, the spring normally maintaining the valve in engagement with the shoulder 48 of the seat which tends to embed itself in the soft face carried by the valve and formed of leather or the like, this face being indicated at 54.

The upper end of the body portion 21 of the valve cage hereinbefore described is spaced below the upper end of the casing 15 and the threads thus exposed form a seat for a wash pipe receiver, indicated generally at 55. This wash pipe receiver has a bore 56 adapted to receive the lower end 55 of the wash pipe and has its upper end

externally screw-threaded, as indicated at 57. The member 58 is a packing gland having at its lower end a threaded bore 59 adapted to engage the external screw-threads at the upper end of the wash pipe receiver, the bore at its upper end being restricted by the inwardly extending shoulder 60 opposing the upper end of the wash pipe and coacting therewith to compress the packing placed therebetween and cause the same to engage against the outer face of the wash pipe. The upper end of the packing gland 58 is frusto-conical in form and if desired may be employed as a seat for a frusto-conical flange of soft metal formed upon the wash pipe, as indicated at 61, to further assist in sealing the same. The wash pipe 57 has secured to the lower end thereof, as by means of pin 62, the upper end of the wire 35, for a purpose presently to appear.

In the use of the device, the wash pipe is seated in the upper end of the wash pipe receiver 55 and pump pressure provided for forcing water therethrough, the pressure being prevented from returning through the screen and casing by the packing gland and frusto-conical seat provided at the upper end of the wash pipe receiver as hereinbefore described. This pressure acting against the piston valve 28, forces the same downwardly until the ports or openings 24 are exposed so that the pressure may pass thereby, any collected water beneath the piston passing out through the openings 25. The pressure within acts against the valve 47, opening the same and the water under pressure passes through the lower end of the casing 15, acting against mud and collected sand in the bottom of the well causing the same to move upwardly at the sides of the casing, permitting the screen and back pressure valve to be seated at the bottom of the well. Accumulated dirt and mud is also washed away from the surface of the screen and caused to come to rest at the top of the sand in which the screen is placed upon release of the pressure. The piston valve and valve 47 are returned to their seats, the soft facing upon the lower valve preventing grains of sand and the like from holding the valve open and the sharp edges of the upper valve permitting the same to shear against anything which may have become caught in the ports 24 and return to its seat. In event the elements against which the valve must act to return to its seat are of such structure that the strength of the spring is insufficient to cause the valve to shear the same when the wash pipe is elevated after the washing is applied, the pull exerted by the wire 35 before breaking, will cause such shearing action, forcing the piston valve upwardly until the sharp edges thereof are firmly

seated in the seat 27 and entrance of water, mud or the like therethrough to the screen effectually prevented. Passage of fluid to the piston valve is likewise prevented by 5 the piston or packing rings 43 and 44 hereinbefore described.

It will be obvious that a back pressure valve constructed in accordance with my invention is a very simple construction and 10 may be very readily applied to the lower end of the screen. When thus applied, the structure thereof permits the use of the wash pipe when desired, the valve automatically closing when the washing pressure is 15 relieved, again sealing the lower end of the screen. It will furthermore be obvious that the structure hereinbefore set forth is capable of many changes and modifications without materially departing from the spirit 20 of my invention and I accordingly do not limit myself thereto except as hereinafter claimed.

I claim:—

1. In combination with a well screen, a 25 valve structure engaged with the lower end of the well screen including a valve opening in response to pressure interiorly of the screen, means for automatically reseating said valve when open, said valve including 30 a cage having a bore, the walls of the bore having openings therethrough, a valve piston slidably fitting the bore and having a seat, said valve being provided with a shearing edge adapted to engage said seat and 35 to have wiping engagement with the bore of the cage.

2. In a device of the type described, a casing adapted for attachment to the lower 40 end of a well screen and provided at its upper end with means for receiving the lower end of a wash pipe, an upwardly seating valve arranged within the casing, a seat for said valve, downward movement of the valve opening communication through 45 the casing to permit passage of water from the wash pipe, yieldable means normally holding the valve against its seat, and means connecting the wash pipe and valve for positively seating the valve.

3. In a device of the type described, a 50 casing adapted for engagement with the lower end of a well screen, a valve cage arranged within the casing and embodying a body portion secured to the walls of the 55 casing and having a bore, said body portion being provided upon its lower end with a depending tube like structure, the bore of which forms a continuation of the bore of the body portion, a piston valve mounted 60 within the bore, openings formed in the upper end of the tube like structure communicating with the bore, a valve seat carried by the body portion at the upper end of the bore and with which the piston valve 65 is adapted to coact, and means normally

holding said piston valve in engagement with said seat.

4. In a device of the type described, a casing adapted for engagement with the lower end of a well screen, a valve cage 70 arranged within the casing and embodying a body portion secured to the walls of the casing and having a bore, said body portion being provided upon its lower end with a depending tube like structure, the bore of which forms a continuation of the bore of the body portion, a piston valve mounted within the bore, openings formed in the upper end of the tube like structure communicating with the bore, a valve seat carried by the body portion at the upper end of the bore and with which the piston valve is 75 adapted to coact, means normally holding said piston valve in engagement with said seat, means at the upper end of the casing 80 for receiving a wash pipe, and means connecting the wash pipe and valve for positively seating the valve upon elevation of the wash pipe.

5. In a device of the type described, a 85 casing adapted for engagement with the lower end of a well screen, a valve cage arranged within the casing and embodying a body portion secured to the walls of the casing and having a bore, said body portion being provided upon its lower end with a depending tube like structure, the bore of which forms a continuation of the bore of the body portion, a piston valve mounted 90 within the bore, openings formed in the upper end of the tube like structure communicating with the bore, a valve seat carried by the body portion at the upper end of the bore and with which the piston valve is 95 adapted to coact, means normally holding said piston valve in engagement with said seat, means at the upper end of the casing 100 for receiving a wash pipe, and means connecting the wash pipe and valve for positively seating the valve upon elevation of the wash pipe, including a breakable wire connected at one end to the valve and at the opposite end to the wash pipe.

6. In a device of the type described, a 105 casing adapted for engagement with the lower end of a well screen, a valve cage arranged within the casing and embodying a body portion secured to the walls of the casing and having a bore, said body portion being provided upon its lower end with a depending tube like structure, the bore of which forms a continuation of the bore of the body portion, a piston valve mounted 110 within the bore, openings formed in the upper end of the tube like structure communicating with the bore, a valve seat carried by the body portion at the upper end of the bore and with which the piston valve is 115 adapted to coact, and means normally holding said piston valve in engagement 120

with said seat, said valve being provided upon the upper end thereof with a peripheral shearing edge having sliding engagement with the walls of the bore and tube like structure.

7. In a device of the type described, a casing adapted for engagement with the lower end of a well screen, a valve cage arranged within the casing and embodying 10 a body portion secured to the walls of the casing and having a bore, said body portion being provided upon its lower end with a depending tube like structure the bore of which forms a continuation of the bore of

the body portion, a piston valve mounted 15 within the bore, openings formed in the upper end of the tube like structure communicating with the bore, a valve seat carried by the body portion at the upper end of the bore and with which the piston valve 20 is adapted to coact, means normally holding said piston valve in engagement with said seat, and an upwardly seating check valve arranged within said casing at the lower end thereof.

25 In testimony whereof I hereunto affix my signature.

ABNER L. SMITH.
